UNITED STATES PATENT OFFICE.

LOUIS G. SCHMIDT AND ANDREW T. McDONALD, OF PHILADELPHIA, PENNSYLVANIA.

WOOD-BENDING MACHINE.

SPECIFICATION forming part of Letters Patent No. 762,092, dated June 7, 1904.

Application filed September 16, 1903. Serial No. 173,416. (No model.)

To all whom it may concern:

Be it known that we, LOUIS G. SCHMIDT, a subject of the Emperor of Germany, and ANDREW T. McDONALD, a subject of the King of Great Britain, both residents of the city and county of Philadelphia, State of Pennsylvania, have invented certain new and useful Improvements in Wood-Bending Machines, of which the following is a specification.

10 Our invention relates to improvements in wood-bending machines, and more particularly to improvements in machines for bending wood for the handles of umbrellas, canes, and like articles.

15 In the accompanying drawings, forming part of this specification, and in which similar letters of reference indicate similar parts throughout the several views, Figure 1 is a plan, partly in section, of our wood-bending machine; Fig. 2, a side elevation, partly in section, of Fig. 1; Fig. 3, a rear elevation, upon an enlarged scale, of one of the carriers for holding a piece of wood during the bending operation; Fig. 4, an enlarged section of 25 part of the machine upon line A A, Fig. 1; Fig. 5, a section of Fig. 4 on line B B; Fig. 6, a section of Fig. 4 on line C C.

a is a frame upon which the machine is carried.

30 b is a former, preferably constructed of metal, which is open at the bottom and ends, and the sides of which, passing front to rear, slant toward one another, while the top, passing from the front to the rear, slopes upward—35 that is to say, at the front the former has a substantially rectangular section which is much longer than high, while at the rear it has a substantially parabolic section which is as high or higher than it is wide.

40 c represents carriers for holding the wood to be bent. They consist of two pieces of metal e f, forming pockets, secured together by a band g. The parts e f of the carriers are open upon their fronts and at their inner sides, so as to facilitate the insertion or removal of the wood to be bent.

u, Fig. 5, represents guides on the lower inner sides of the former b which are adapted to engage and carry the ends e f of the

carriers c or, if the carriers be not used, the ends of the sticks. These guides confine the ends of the sticks, prevent them from spreading, and insure the bending upward of the sticks, so that their outer sides will hug the under face of the former while they are being driven through it.

h is a shaft, driven in any suitable manner, which carries a cam or cams i, which are adapted during their revolution to engage and move forward the plungers j, which are carried by suitable guides k, carried by the frame a.

The piece of wood to be bent is placed in one of the carriers c, and this latter is then placed in the machine between the plungers j and the front of the former b. Upon the forward movement of the plungers by the cams i the carrier and the piece of wood carried thereby is driven into the forward end of the former b. The carrier c is so placed in the machine that the band or strap g will be above the wood to be bent, not only that the under side of the wood may be exposed directly to the heat and steam during the process of bending, as presently described, but to prevent a direct contact between the wood and the former b, as well as to prevent its tearing or splintering upon the outside during the bending. A carrier c having been driven into the forward end of the former b and the operative part of cam i having been moved past the plunger, the latter is immediately drawn back into its first position by a weight l and cord m or by any other suitable device. As soon as the plunger has been returned to its first position another carrier c, with a piece of wood to be bent, is placed in between it and the front of the former b, and upon the forward movement of the plunger this carrier and its contents is driven into the former b, driving before it the first carrier. Carriers are thus successively driven into and through the former b.

Within the former b are means for steaming or for heating the wood, both or either. We have shown the former b furnished with three tubes running lengthwise of it, the tubes n o being gas-carrying tubes and the tube p being a steam-

carrying tube. The tubes are furnished with perforations to permit the escape of gas and steam. The gas is lighted and heats the wood upon the inner side during the bending, while 5 the steam at the same time plays upon it. In order to prevent the outer part of the wood from being charred by the flames, we preferably place between it and the band *g* a sheet of asbestos *v*, Fig. 5. The carriers and the 10 bent wood carried by them pass out the rear end of the former *b* and along a guide or table *s*, Figs. 1, 2, and 4, during which time they may be played upon by streams of water from pipes *w x*, the former above and the latter 15 below them.

In bending very hard woods—boxwood, for instance—it is advisable to thoroughly steam them before putting them through the machine; but with woods of ordinary hardness 20 no preliminary steaming is necessary.

The wood to be bent being frequently more or less crooked will in some cases bend up the band or strap *g*, so that the carrier carrying it cannot well enter the forward end of the 25 former *b*. In cases of this nature we make use of the lever *t*, which is pivoted upon the top of the former at its front and center and which is adapted to be moved down to engage the top of a strap *g*, as shown in Fig. 4, to 30 press this strap and the wood in the carrier down until the carrier has been forced into the former.

u (best shown in Fig. 5) represents guides in which the ends *e f* of the carriers *c* travel 35 in their passage through the former.

The end *f* of the carrier is shown as larger than the end *e*. This is because one end of a cane or umbrella handle is usually larger than the other. If the ends of the stick to be bent 40 are of the same diameter, both ends of the carrier would be preferably of the same size.

v represents the stick to be bent.

y, Fig. 1, represents springs placed in front of the former *b*, which permit the carriers to 45 pass into, but which prevent them from moving out of, the front of the former after they have once entered it.

It is the usual practice to place upon the outer side of a piece of wood to be bent a flexible strip of metal like our strip *g* to prevent the splintering or tearing of the wood upon the outside of the bend. This flexible strip of metal is necessarily thin, and if there be a weak place in the wood, or if the wood be 50 thinner at one place than at another, the bending will first take place at this point, the wood bending in an angular manner instead of in a regular curve. Our former effectually prevents this fault, as it is so strong that it can- 55 not be bent out of its shape by any pressure that would be necessary to drive the wood through it. As the wood is driven through the former its ends gradually approach one another and its middle buckles upward against 60 the former, which it closely hugs until it is 65

driven out of its rear end with a bend of the same form as that of the rear end of the former.

Having thus described our invention, we claim as new and desire to secure by Letters Patent—

1. In a wood-bending machine in combination, a former having a continuous smooth under surface substantially flat at the forward end, the top gradually rising and the sides gradually approaching one another toward the 75 rear end, so that at the rear end the under side of said former has the shape of the outer curve of the desired bent article, said former being adapted to engage at all times during the bending the outer side of the stick, guides 80 upon the outer side of said former for engaging the ends of the stick, and means for successively driving the sticks through said former.

2. In a wood-bending machine, in combination, a former having a continuous under surface substantially flat at the forward end, the top gradually rising and the sides gradually approaching one another toward the rear end, so that at the rear end the under side has the shape of the outer curve of the finally-bent 90 article, said former being adapted to engage the outer side of the stick continuously during the bending, guides upon the lower sides of said former for engaging the ends of the sticks, detents at the forward end of said 95 former for permitting the entrance and preventing the withdrawal of the sticks at this end, and means for successively forcing the sticks to and through said former.

3. In a wood-bending machine, in combination, a former having a continuous smooth under surface, substantially flat at the forward end and at the rear end having the shape of the outer curve of the finally-bent article, guides upon the lower side of said former, a carrier 105 having metal ends to receive the ends of the stick and to engage the guides on said former, and a strap to cover the outer side of the stick, and means for driving successive carriers into said former.

4. In a wood-bending machine, in combination, a former having a continuous smooth under surface substantially flat at the forward end and at the rear end having the shape of the outer curve of the finally-bent article, guides 115 at the lower sides of said former for engaging the ends of the sticks to be bent, means within said former for softening the sticks, and means for driving the sticks through said former.

5. In a wood-bending machine in combination, a former within which the sticks are bent, means for driving said sticks through said former, means within said former for softening the sticks, and means without the rear end of said former for playing water upon the 120 heated and bent sticks.

6. In a wood-bending machine, in combination, a former having a continuous smooth under surface substantially flat at the forward end, and curving rearwardly so that at the rear 130

- end it has the shape of the outer curve of the finally-bent article, guides upon the lower sides of said former, steam-pipes and gas-burners within said former, a plunger for successively driving the sticks into said former and against one another, a cam for actuating said plunger, and means for returning said plunger to its first position after having been operated upon by said cam.
- 5 7. In a wood-bending machine, in combination, a former having a continuous smooth under surface substantially flat at the forward end and curving rearwardly so that at the rear end it has the shape of the outer curve of the finally-bent article, guides at the lower inner 15 sides of said former, a carrier having pocketed ends for the ends, and a strap for the outer curve of the stick, means for heating said sticks while passing through said former, means for driving said carriers and sticks through said 20 former, and a lever pivoted to the said former and adapted to engage and straighten said sticks before entering said former.
